UNITED STATES PATENT OFFICE.

GEORGE S. WHYTE, OF CHICAGO, ILLINOIS.

NON-ROTATING WIRE ROPE.

952,161.

Specification of Letters Patent. Patented Mar. 15, 1910.

Application filed November 1, 1906. Serial No. 341,819.

To all whom it may concern:

Be it known that I, GEORGE S. WHYTE, a citizen of the United States, residing at Chicago, in the county of Cook and State of Illinois, have invented a certain new and useful Improvement in Non-Rotating Wire Rope, of which the following is a specification.

My invention relates to wire ropes and the object of my invention is to provide a non-rotating wire rope especially for use in mine and elevator shafts where there are no guides controlling the load carried to prevent its rotating on its axis.

15 My invention consists in an arrangement of the strands forming the wire rope which renders it non-rotating.

It also consists in details of construction which will be hereafter more fully described 20 and claimed as the specification proceeds.

Figure 1 illustrates a rope constructed in accordance with my invention the upper portion representing the complete rope, the intermediate portion, the rope with the outer 25 layer of strands removed, and the bottom portion the core. Fig. 2 is a sectional detail view through the complete rope.

Wire rope as heretofore usually made, comprises a core of hemp around which is 30 helically wound a layer of strands, each strand being made up of a plurality of single wires twisted together. About six such strands are usually employed, which will closely and firmly cover a core of approximately the same diameter as one strand. If 35 a larger number of strands be employed a larger core is necessitated, and with such increase in the size of core the rope is liable to deformation or collapse under 40 strain. Hence it may be considered that a practicable rope of this character ought to have about six strands. Such a rope in passing over a sheave cannot have more than three points of contact therewith in the 45 plane of any cross-section. It is evident to any one familiar with the art that the greater the number of points of contact of a wire rope with its sheave in the plane of any cross-section and the more nearly cylindrical its form, the less will be the wear 50 upon the individual wires in contact with the sheave and the more uniform the distribution of wear upon the sheave, thereby prolonging the life of both.

55 When a load is suspended upon a wire

rope of the ordinary construction as above described, without restraining guides or guys, the strands of the rope have a tendency to untwist and thus cause the end of the rope to rotate or spin with its load. 60 This tendency to rotate is very objectionable. By my improved construction as hereinafter shown in the drawings and described in the specification and claims, I secure a rope having a much larger number of points 65 of contact in the plane of any cross-section, more nearly cylindrical in form, and wholly without tendency to spin under tension.

In the drawings *a* is a core of hemp or other suitable material which serves as a 70 cushion on which I lay helically a plurality, preferably six, of strands *b* each made up of single wires laid or twisted helically together. Around this layer of strands *b* I lay helically in the opposite direction a plurality, preferably twelve, of similar strands *c*. In order that the tendency of the two layers 75 of strands to untwist or spin may neutralize each other, I give the strands *b* a considerably shorter "lay" or twist than the strands 80 *c* of the other layer, so that the relatively strong tendency of the inner layer to untwist shall be practically equalized by the weaker tendency of the larger number of strands in the outer layer to untwist in the 85 opposite direction. As a specific example of such construction of rope in which the lay of the strands of the inner layer is sufficiently shorter than the lay of the strands of the outer layer to balance or equalize the 90 torsion or tendency to untwist due to the greater number of strands in the outer layer, a ratio of 1 to 1.87 between the lay of the strands of the inner layer and that of the strands of the outer layer may be employed. 95 It will also be seen that with my improved rope there being twice as many strands in the exterior layer as in the same diameter of the ordinary construction, there will be twice as many points in contact with the 100 sheave in the plane of any cross-section, and because of the smaller size of the strands, the rope approaches more nearly a cylindrical form. It will also be seen that if a single strand *c* is broken or cut the rope 105 is weakened only one-third as much as if a strand were severed in a six strand rope.

The distinction between "strand" and "rope" should also clearly be borne in mind, a strand being composed of single 110

wires twisted together, while a rope is always composed of a series or plurality of "strands". A strand cannot be used practically as a rope, because the exposed wires are not bound together and are liable to become loosened, and a broken wire will fall out or can be bodily drawn out of the strand. In a rope every wire is held firmly in place by the pressure of the adjacent strands, and if broken cannot become loosened or be withdrawn from the rope.

Having thus described my invention what I claim as new and desire to secure by Letters Patent, is:

- 15 1. In a wire rope, in combination, a core, a series of strands laid helically there-around and another series of similar strands laid helically around the first series in the opposite direction, each strand being composed of a plurality of wires laid helically together, the strands of the inner layer having such shorter "lay" than those of the outer layer as will balance or neutralize their
- 20

opposed torsional strains, as and for the purpose specified.

2. A wire rope comprising in combination, a layer composed of a plurality of strands laid helically in contact with each other, each strand being composed of a plurality of individual wires laid helically with relation to each other, and an outer layer of approximately twice as many similar strands helically and oppositely laid thereon, the strands of the inner layer having such shorter lay or twist than the strands of the outer layer that their tendency to untwist will neutralize the tendency of the outer layer of strands to untwist in the opposite direction.

In witness whereof, I have hereunto subscribed my name in the presence of two witnesses.

GEORGE S. WHYTE.
